UNITED STATES PATENT OFFICE.GEORGE J. ZURSTADT AND WILLIAM ABIGT, OF EVANSVILLE, INDIANA.*DESIGN FOR A PARLOR HEATER.

Application filed April 12, 1927. Serial No. 21,568. Term of patent 14 years.

To all whom it may concern:

Be it known that we, GEORGE J. ZURSTADT and WILLIAM ABIGT, citizens of the United States, residing in Evansville, county of Vanderburg, and State of Indiana, have invented a new, original, and ornamental Design for a Parlor Heater, of which the following is a specification, reference being made to the accompanying drawing, forming a part thereof.

We claim:

The ornamental design for a parlor heater as shown.

GEORGE J. ZURSTADT.
WILLIAM ABIGT.
